UNITED STATES PATENT OFFICE.

CHARLES E. GERVAIS, OF JACKSONVILLE, FLORIDA, ASSIGNOR TO FRANK E. WAYMER,
OF JACKSONVILLE, FLORIDA.

DOUCHE-NOZZLE.

1,249,375.

Specification of Letters Patent. Patented Dec. 11, 1917.

Application filed May 25, 1916. Serial No. 99,866.

To all whom it may concern:

Be it known that I, CHARLES E. GERVAIS, a citizen of the United States, residing at Jacksonville, in the county of Duval, State of Florida, have invented certain new and useful Improvements in Douche-Nozzles; and I do hereby declare the following to be a full, clear, and exact description of the invention, such as will enable others skilled in the art to which it appertains to make and use the same.

This invention relates to douche nozzles and more particularly to such nozzles designed especially for vaginal irrigations, and has for its object to provide a douche nozzle which will conform to the vaginal anatomy with respect, especially to the cervix uteri and the portion of the vaginal passage lying directly thereabove. It is well known that this particular portion of the vagina is most difficult of access with the usual type of douche nozzle, since it is practically cut off by the cervix, and the insertion of the ordinary douche nozzle has a tendency to force the cervix upwardly, resulting in a fold of tissue at the union of the cervix with the vaginal wall directly above the cervix, which fold has a tendency to retain and propagate any pathogenic organisms which may be present. It is a primary purpose of the present invention to produce a nozzle which will thoroughly irrigate all portions of the vagina while permitting the cervix to remain in its normal position.

It is also well known that in many cases the vaginal wall will form in folds at other points, and it is obvious that wherever such a fold occurs the difficulty of properly irrigating the tissue is materially increased. It is an object of the present invention to provide a nozzle so constructed that it may be manipulated in a way to eliminate such folds thus making possible the thorough irrigation of the entire vaginal surface.

Another object is to provide a structure in which that portion of the nozzle which enters above the cervix will be so constructed as to cause a spreading of the irrigating fluid in the form of a rosette or circular spray.

In the drawing:

Figure 1 is a perspective view of the complete nozzle;

Fig. 2 is a longitudinal section taken on line 2—2 of Fig. 1, and

55

Fig. 3 is a transverse section on line 3—3 of Fig. 1.

Referring now to the drawings the present invention comprises a central tube 5 provided at one end with an enlargement 6 in the form of the usual neck and swell for engagement within the end of a rubber tube leading to a suitable reservoir, neither the tube nor the reservoir being shown.

At the inner end of the enlargement 6 there is a circumscribing flange 7 and inwardly of this flange there is a threaded portion 8 slightly larger than the tube 5 and slightly smaller than the flange 7. The interior passage 9 of the tube communicates, of course, with the interior passage 6' of the enlargement 6.

At its end portion opposite to the enlargement 6 the tube 5 is provided with a plurality of spaced lateral openings 10 which communicate with the passage 9 and, as illustrated, the passage 9 opens through the end of the tube which is distant from the enlargement 6.

The major portion of the tube 5 is surrounded by a cage 11 which includes an annular member 12 internally threaded as shown at 13 for engagement with the threads of the portion 8, so as to rest with its face 14 against the flange 7. This face 14 is flat but the opposite face 15 is curved from the periphery of the central opening of the member to the periphery of the face 14 so that the member has approximately the shape of a segment of a sphere.

A plurality of equi-distant openings 16 are formed through the member 12 from the face 14 to the face 15, these openings surrounding the central opening 13 in a circular series.

Secured to the face 15 of the member 12 there are a plurality of longitudinally extending rods 17, one rod being located between each pair of openings and these rods project at their opposite ends beyond the free end of the tube 5 where they are turned inwardly as indicated at 18 and are secured to a conical member 19 adjacent to the base of this member, the member 19 lying with its apex directed toward the free end of the tube 5 and directly opposite the open

end of the passage 9 thereof. As shown in the drawing the conical member 19 is spaced from the end of the tube 5.

The several rods 17 are spaced considerable from each other as illustrated and the spaces between the rods are considerably greater than the diameters of the rods.

Between their ends but at a point nearer the conical member 19 than the member 15 10 the cage 11 is circumferentially constricted, this being produced by curving the rods of this point inwardly toward the tube 5.

In use the cage 11 is inserted within the vaginal passage, the end of the cage adjacent to the member 19 being passed beyond the cervix and the member 15 being disposed in contact with the labia minora or with the walls of the vagina directly thereabove. It will be understood that, though 15 the cervix may be lifted by the engagement of the free end of the cage therewith, it will be permitted to return to its normal position when the outer end of the constricted portion of the cage has passed the cervix.

20 When the irrigating fluid is permitted to pass through the tube 5 it will find egress through the openings 10 to the surface of the cervix and by reason of the fact that the cage holds the vagina slightly distended, the 25 fluid will have free passage down to the openings 16 and out therethrough.

The irrigating fluid will also find egress through the open end of the passage 9 and, striking the surface of the cone member 19 30 will be deflected in the form of a rosette or circular spray to thoroughly irrigate the tissue surfaces above the cervix.

During the process of irrigation a rotary motion imparted to the nozzle will result 35 in movement of the rods 17 over the mucous membrane of the vagina, thus eliminating any folds therein and exposing all portions thereof to the action of the fluid. By reason of the fact that the rods 17 are considerably spaced from each other the tissue 40 may extend between these rods and thus receive the full action of the irrigating

fluid. It will thus be seen that the spacing of the rods to a relatively great extent is important and that it is also important that 50 this rod structure be employed to prevent abrasion of the tender and sensitive tissues during the rotary movement of the nozzle.

By reason of the fact that the tube 5 has threaded connection with the cage, the rod 55 may be turned with respect to the member 15 which will result in movement of the free end of the tube toward or away from the cone member 19 and this will cause a variation in the force of the circular spray 60 as well as in its volume. Thus, after the nozzle has been inserted the tube may be manipulated to vary the circular spray to produce the best result.

What I claim is:—

65 A douche nozzle consisting of a base member having a tube-attaching stem and a radiating flange beyond which it is exteriorly threaded, an annular member screwed onto the threaded portion and having perforations therethrough ranging longitudinally of the base member, a cone having rods radiating from its base and ranging with compound curves past the apex of the cone with the chords of their curvatures parallel with 70 the extension of the axis of the cone past its apex, the ends of the rods being engaged in alternate perforations of the annular member and a tube carried by the base member and forming a continuation of the bore 75 thereof, the tube extending with its axis coincident with the extension of the axis of the cone beyond its apex, equidistant from and in spaced relation to the rods, the tube having its end opposite to the base in close proximity to the cone to discharge against the wall thereof and having radial perforations in its free end portion.

80 In testimony whereof, I affix my signature, in the presence of two witnesses.

CHARLES E. GERVAIS.
